UNITED STATES PATENT OFFICE.

CONYERS BUTTON, OF PHILADELPHIA, PENNSYLVANIA.

DESIGN FOR STOCKING FABRIC.

Specification forming part of Design No. **6,667**, dated May 27, 1873; application filed May 13, 1873.

To all whom it may concern:

Be it known that I, CONYERS BUTTON, of the city and county of Philadelphia, State of Pennsylvania, have invented a Design for a Stocking Fabric, of which the following is a specification:

My design for a stocking fabric is fully represented by the figure in the accompanying drawing, and consists of alternating stripes A and B, each consisting of a series of minor parallel stripes, bars, or ribs, of different shades or colors, arranged in the manner too clearly shown by the drawing to need minute description.

I prefer that the stripe A shall be dark, and the stripe B light, in order to present a pleasing contrast; but this is immaterial, and forms no part of the design.

Irrespective of the colors employed, I claim—

The design for a stocking fabric, substantially as described, and as represented in and by the accompanying drawing.

In testimony whereof I have signed my name to this specification in the presence of two subscribing witnesses.

Witnesses: CONYERS BUTTON.

W.M. A. STEEL,
L. BOSWELL.
